UNITED STATES PATENT OFFICE.

PAUL E. DAVIS, JR., OF DETROIT, MICHIGAN.

WARDROBE TRUNK.

Application filed July 28, 1924. Serial No. 728,735.

This invention relates generally to wardrobe trunks and consists of certain novel features of construction, combinations, and arrangements of parts as will be more fully described and particularly pointed out in the appended claim.

In the accompanying drawing:

Figure 1 is a front elevation of a shoe box embodying my invention mounted within the wardrobe section of a trunk.

Figure 2 is a horizontal sectional view taken on the line 2—2 of Figure 1 and showing the box in dotted lines when swung outwardly.

Figure 3 is a perspective view of the shoe box section of the hinge.

Figure 4 is a perspective view of the trunk section of the hinge.

Figure 5 is a fragmentary perspective view of the box and wardrobe section of the trunk showing the latching means.

Referring now to the drawings in which like characters of reference designate corresponding parts throughout the several views, the numeral 1 designates a shoe box which is preferably located within and at the front portion of the wardrobe section 2 of a suitable trunk. The box 1 may be any shape desired but is preferably of the proper length to fit easily between the side walls 3 and 4 respectively of the wardrobe section and is of the proper width to permit the garments supported in the wardrobe section to hang in the rear of the box. As shown, the box is preferably rectangular in shape and is formed of two sections 5 and 6 respectively which are hinged together at the bottom and are detachably connected at the top by means of suitable snap fasteners 7.

For supporting the box within the wardrobe section of the trunk, I preferably provide a pair of suitable hinges 8 which connect one end of the box to the wall 3 of the wardrobe section. As shown, each hinge preferably comprises the main supporting part 9 and the cooperating part 10. The main part 9 of each hinge is preferably in the form of a flat plate that is provided at the lower end of its outer edge with a longitudinally extending eye 11, while the cooperating part 10 of each hinge is also in the form of a flat plate that is provided at the upper end of its outer edge with a longitudinally extending eye 12. In order that the box may be readily removed from the wardrobe section of the trunk, the eyes 12 of the

hinge parts 10 preferably rest on the eyes 11 of the hinge parts 9 and are connected thereto by suitable pintles 13 which preferably are fixed in the eyes 12 and are free to turn in the eyes 11.

To provide a strong and durable construction I preferably provide the side walls 3 and 4 of the wardrobe section of the trunk with metallic reinforcing strips 14 and 15 respectively which are preferably rigidly secured to the side walls at the forward edges thereof and are provided with longitudinally extending laterally projecting flanges 16 and 17 respectively which are substantially flush with the front edges of the wardrobe section and serve as abutments for the drawer receiving section 2' of the trunk. The main parts 9 of the hinges are preferably riveted to the lateral flange 16 of the reinforcing strip 14, while the cooperating parts 10 are preferably rigidly secured to one end of the front section 5 of the box.

For holding the box in proper position within the wardrobe section of the trunk, I preferably provide a suitable spring pressed bolt 18 that is slidably mounted in a suitable housing 19 mounted on the top of the outer box section 5 and is adapted to be projected through a suitable opening 20 in the base 21 of a substantially U-shaped bracket or keeper 22 that is rigidly secured to the side wall 4 of the wardrobe section of the trunk.

From the foregoing description it will be readily apparent that the box may be readily swung outwardly as indicated by the dotted lines in Figure 2 of the drawing to gain access to the interior of the box, or it may be removed entirely from the wardrobe section of the trunk by merely retracting the bolt 18 and lifting the box by the handle 23 so that the pintles 13 will be withdrawn from the eyes 11 of the hinge parts 9. It will also be apparent that the bolt 18 will effectively hold the pintles 13 in engagement with the eyes 11 of the hinge parts 9 when the box is disposed in the position shown in Figure 2 of the drawing, and consequently will prevent the box from moving within the wardrobe section when the trunk is being moved about or shipped. Furthermore the flange 16 strengthens the strip 14 which materially reinforces the side wall 3 of the wardrobe section of the trunk so that the entire structure is more durable and serviceable for use.

While it is believed that from the foregoing description the nature and advantages

of the invention will be readily apparent, I desire to have it understood that I do not limit myself to what is herein shown and described, and that such changes may be resorted to when desired as fall within the scope of what is claimed.

What I claim as my invention is:

The combination with a trunk having a wardrobe section, of a shoe box mounted within the wardrobe section to move horizontally and vertically, means for holding the box in a predetermined position within the section comprising a spring pressed bolt slidably mounted on the box, and a bracket 10 mounted in the wardrobe section, said

bracket having an aperture to receive said bolt, and means for mounting the box including a hinge part secured to a wall of the section having a vertical eye, a hinge part secured to the box having a vertical eye resting on the eye aforesaid, a pintle fixed in the last-mentioned eye and freely movable in the first mentioned eye, said pintle being adapted to turn within the first mentioned eye to permit the box to swing horizontally and being adapted to move longitudinally of the first mentioned eye to permit the box to be removed from the wardrobe section. 20 25

In testimony whereof I affix my signature.

PAUL E. DAVIS, Jr.
